COLLAPSIBLE CAMP STOVE

Teddy R. Pope, Sr., Memphis, Tenn.

Application January 2, 1946, Serial No. 638,675

5 Claims. (Cl. 126—9)

1

This invention relates to collapsible camp stoves, and has particular reference to a stove which is so constructed that it may be folded into a compact flat package for transportation, all the parts of the stove being connected so that either when set up for use or folded for transportation there are no loose parts which may be displaced.

The objects of the present invention are:

To provide a simple and efficient stove of rugged construction which may be readily set up for use and as readily broken down and nested for transportation in which the parts are hinged together so that they may be compactly folded without disconnection the one from the other into a flat package.

The means by which the foregoing and other objects are accomplished, and the method of their accomplishment, will readily be understood from the following specification upon reference to the accompanying drawings, in which:

Fig. 1 is a plan view of the stove.

Fig. 2 is a side elevation; and

Fig. 3 a front elevation, all as set up for use.

Fig. 4 is a section taken on the line IV—IV of Fig. 3 with the parts partially unfolded.

Fig. 5 is a side view with the parts of the stove folded for transportation, the top being slightly raised; and

Fig. 6 is an outline view of the parts and their hinge connections.

Referring now to the drawings in which the various parts are indicated by numerals:

The stove comprises a front 11, a back 13, sides 15 and 17, a bottom 19 and a top 21, all of flat sheet metal, and with the exception of the top, which may be octagonal, of rectangular shape.

The front 11 and back 13 are of equal height and the sides 15 and 17 of greater height, the top of the front, back and sides being flush when the stove is assembled for use, and the sides being of greater depth than the front and back so that they project therebelow and support the bottom of the stove above the supporting surfaces. The bottom portions of the sides are preferably cut out to form legs 23.

Adjacent the top, openings 25 are cut in the sides by which the stove may be shifted. Adjacent the cut-out portions of the sides horizontal slots 27 are provided for engagement and support of the bottom 19.

The top and bottom are provided with draft holes 29 and 31 respectively, preferably arranged in a series of rows, as shown. The front, back and sides are also preferably provided with an ad-

2

ditional horizontal row each of draft holes 33 slightly above the level of the bottom when the stove is assembled.

The front 11 is hinged to the front edge of the bottom 19 by interior hinges 35 which are on the upper side of the bottom and rear side of the front so that the front may be folded over and on top of the bottom for nesting. The bottom is hinged to the lower edge of the back 13 by exterior hinges 37 which permit the bottom to be swung into a horizontal position when the back is set up in vertical position and also permit the bottom to be swung from such horizontal position around to a position against the outside of the back for nesting.

The sides 15 and 17 are respectively hinged to opposite side edges of the back 13 by internal hinges 39, 41 so that one of the sides, as the side 15, may be folded inward flat against the back, and the other side 17 be folded inward flat against the previously folded side 15 for nesting. The side 15 is preferably cut out to form notches 42 which avoid the hinges 41 in such folded position of the sides. The top 21 is hinged to this second side 17 by hinges 43 external to both thereof, and so constructed that the top may be swung down into overlying relation on the edges of the sides, front and back when the stove is set up, or may be folded outward and flat against the outer surface 30 of the side 17 for nesting.

The bottom 19 is provided with lugs 45 projecting from its opposite sides adapted to engage the horizontal slots 27 in the sides 15 and 17 when the stove is set up for use.

Projecting from the side edges of the front are threaded bolt ends 47 which are adapted to be engaged in suitably positioned holes 49 in the front edges of the sides and clamped by wing nuts 51 when the stove is set up.

Folded for transportation, as shown in Fig. 5, the front 11 underlies the bottom 19 which in turn is overlain successively by the back 13, the side 15, and the side 17 with the top lying on the side 17.

In setting up the stove for use, the bottom 19 is swung outward away from the back into a generally horizontal position, as shown in Fig. 4, and the front swung around and outward and extending forwardly therefrom. The side 17 with the top attached is swung upward and outward away from the back 13, and the side 15 swung upward and oppositely outwardly therefrom and the back raised to vertical position. The sides 15 and 17 are swung inward toward parallelism 55 and to positions at right angles to the back 13.

and the bottom 19 raised so that the lugs 45 may be engaged with the horizontal slots 27 in the sides. The front 11 is brought upward to a vertical position and as the slots 27 of the sides engage the lugs 45 of the bottom, the bolt ends 47 of the front are engaged in the holes 49 of the sides, the wing nuts 51, which have previously been removed, are engaged with the bolt ends and tightened up to complete the assembly. Fuel is placed in the stove and lighted and the top 21 is swung over into place resting on the front, back and sides and the stove is ready for use.

I claim:

1. A collapsible stove comprising flat rectangular sheets of metal respectively adapted to form a front, back, sides, bottom and top of a hollow prism, means hinging the back edges of the sides respectively to the opposite side edges of the back, means hinging the rear edge of the bottom to the lower edge of the back, means hinging the lower edge of the front to the forward edge of the bottom, and means hinging one edge of the top to the upper edge of one of the sides, the means hinging said sides, front, bottom and back together, preferably holding the top of said sides, front and back at even height to receive said top, said sides being of greater depth than said front and back and cut away intermediate their width below the level of said ends to form supporting feet, and being slotted at the level of the lower end of said back and of said bottom hinged thereto, said bottom having along its opposite side edges projecting lug portions adapted to engage in said side slots, and means carried by said front engageable with the front portions of said sides to secure said sides to said front with said bottom lugs in supported engagement with said side slots.

2. A collapsible stove comprising flat rectangular sheets of metal respectively adapted to form a front, back, sides, bottom and top of a hollow prism, means hinging the back edges of the sides respectively to the opposite side edges of the back, means hinging the rear edge of the bottom

to the lower edge of the back, means hinging the lower edge of the front to the forward edge of the bottom, and means hinging one edge of the top to the upper edge of one of the sides, said sides being of greater depth than said front and back and projecting therebelow, to support said front and back above the level of the surface on which they may be placed, said sides being slotted at the level of the lower end of said back and of said bottom hinged thereto, said bottom having along its side edges projecting lug portions adapted to engage in said side slots, and means carried by said front engageable with the front portions of said sides to secure said sides to said front with said bottom lugs in supported engagement with said side slots.

3. A stove in accordance with claim 2, in which said bottom and top are provided with draft openings.

4. A stove in accordance with claim 2, in which said bottom and top are provided with draft openings and said sides are provided with additional draft openings immediately above said bottom.

5. A stove in accordance with claim 2, in which said bottom and top are provided with draft openings and said front and back are provided with additional draft openings immediately above said bottom.

30 TEDDY R. POPE, SR.,
